CLAIM

The ornamental design for a modular intermodal stackable battery system, as shown and described.

DESCRIPTION

FIG. 1 is a top plan view with top cover installed;
FIG. 2 is a top plan view with top cover removed;
FIG. 3 is a bottom view;
FIG. 4 is a front elevational view;
FIG. 5 is a rear elevational view;
FIG. 6 is a left side elevational view;
FIG. 7 is a right side elevational view;
FIG. 8 is a left side perspective view with top cover installed;
FIG. 9 is a left side perspective view with top cover removed;
FIG. 10 is a right side perspective view with top cover installed;
FIG. 11 is a right side perspective view with top cover removed;
FIG. 12 is a left side perspective view with dual stacked units and top cover installed; and,
FIG. 13 is a left side perspective view with dual stacked units and top cover removed.
